MANUFACTURE OF WASHERS

John Albert Chappuis, Neuchatel, Switzerland

Application March 20, 1939, Serial No. 263,009
In Great Britain September 30, 1938

4 Claims. (Cl. 10—86)

This invention relates to a method of making washers from wire by bending it into rings and then subjecting the rings to a pressing operation.

According to the present invention, the washers are manufactured from wire of suitable section for bending into rings by forming the rings and then flattening these rings between dies so as to cause the metal to flow transversely or radially inwardly towards the axis of the ring and thus reduce the dimension of the section in a direction parallel to the axis of the ring and increase the dimension thereof in a direction at right angles to the axis of the ring.

Further, if required, the press tools may be shaped to press the metal into flattened form, but with a chamfered edge to the ring.

The wire from which the washers are to be made is of a cross sectional shape which allows it to be readily bent into a ring, and wire of circular section may be used if desired. Other cross sectional shapes may be used for the wire, but the section should be such that the wire can be bent into a circular ring without cracking at the outer periphery or unduly crushing at the inner periphery.

If required, the wire rings may be made individually by cutting off lengths of wire and bending them into ring form. Alternatively, an indefinite length of wire may be coiled so as to form a helix, and this helix may then be severed at one side parallel to its axis so as to divide it into a number of elements, each consisting of one, two or more turns of wire, such elements being of helical form. These helical elements of wire when placed in the dies in the press are readily cold-forged into flat washer form.

Referring to the drawing:

Figure 1 is a view in side elevation showing the first stage in the manufacture of washers according to one of the methods which may be used in carrying this invention into effect.

Figure 2 is a view in side elevation illustrating the second step of the method.

Figure 3 is a sectional view in side elevation showing the completed washer.

Figure 4 is a sectional view in side elevation showing the dies before the pressing operation.

Figure 5 is a sectional view in side elevation showing the dies after the pressing operation.

One method of carrying the invention into effect is to form the wire into a helical coil as shown in Figure 1. It will be seen that in this coil certain of the turns of the coil, shown at 10, are in contact with each other, while other coils at the left-hand end, shown at 11, are spaced

from each other. It is preferred to open out the end turns of the coil in this way in order to provide clearance for the tools used in severing the individual turns one by one.

- 5 The turns of the coil are separated by a shearing action producing an element 12, as shown in Figure 2. This element is conveyed by suitable means to press tools 13, 14, and the element, while still held in a suitable holder, is engaged 10 at opposite sides by a punch and an anvil 13, 14 before the holder releases the element. When the tools 13, 14, have engaged opposite sides of the element, the holder is released from the element and moved away, and the tools, 13, 14, then advance together until the shoulder 15 of the anvil 14 engages the end of a sleeve 16 when the movement of the punch 14 is arrested, and the anvil 13 continues to advance until the pressing operation is completed as shown in Figure 5. 15 It will be appreciated that the gripping of the element 12 between the press tools 13, 14 centralizes the element in relation to the tools. Further, it will be seen that the anvil 14 works in a collar or die 17 which serves to prevent the 20 outward flow of the metal of the element under pressure.

The element is made of the same diameter as the internal diameter of the die 17, and the holder can drop the element into the die 17 and on 25 to the die 14. To facilitate this, the entrance end to the die 17 may be chamfered as shown at 18. The radial flow of metal under pressure is inwards.

When the elements 12 are cut from the coil 11, 30 the cut may be slightly oblique so that when the element is being pressed, danger of the ends overlapping will be eliminated.

The means for severing the elements 12 and 35 conveying them to the press tools 13, 14, and the means for operating the press tools are described in the specification of my concurrent patent application No. 304,442 and as described therein, the anvil 14 may act as an ejector.

Instead of making the rings or elements by 40 severing individual turns from a coil, the rings may be made by severing suitable lengths of wire and then bending the length into a ring.

What I claim then is:

1. A method of manufacturing washers from 45 circular wire elements of helical form including the steps of pressing the elements axially to convert them into rings having unsecured ends, continuing the axial pressure while supporting the circumference against outward movement, but 50 allowing the metal to flow inwardly towards the

centre to change the shape of the cross section of the metal by reducing the dimension in an axial direction and increasing the dimension in a radial direction.

2. A method of manufacturing washers from circular wire rings having unsecured ends including the steps of feeding the rings one by one into combined gripping, conveying and pressing means conveying the rings so held into a collar supporting the circumference against outward movement, pressing the rings axially while allowing the metal to flow inwardly towards the centre to change the shape of the cross section of the metal by reducing the dimension in an axial direction and increasing the dimension in a radial direction and conveying the rings out of the collar.

3. A method of manufacturing washers from circular wire elements of helical form including the steps of feeding the elements one by one into combined gripping, conveying and pressing means, conveying the elements thereby into a collar supporting the circumference against out-

ward movement, pressing the elements axially to convert them into rings having unsecured ends, continuing the axial pressure to change the shape of the cross section of the metal by reducing the dimension in an axial direction and increasing the dimension in a radial direction and conveying the rings out of the collar.

4. A method of manufacturing washers from circular wire rings having unsecured ends including the steps of feeding the rings one by one into combined gripping, conveying and pressing means, guiding and conveying the rings so held into a collar, supporting the circumference against outward movement, pressing the rings axially while allowing the metal to flow inwardly towards the centre to change the shape of the cross section of the metal by reducing the dimension in an axial direction and increasing the dimension in a radial direction and conveying the rings out of the collar and releasing them from the continued gripping, conveying and pressing means.

JOHN ALBERT CHAPPUIS.
